UNITED STATES PATENT OFFICE.

OTIS W. SCHOFIELD, OF MONTPELIER, IDAHO.

HATBAND.

974,605.

Specification of Letters Patent.

Patented Nov. 1, 1910.

Application filed October 23, 1909. Serial No. 524,174.

To all whom it may concern:

Be it known that I, OTIS W. SCHOFIELD, a citizen of the United States, residing at Montpelier, in the county of Bear Lake and 5 State of Idaho, have invented new and useful Improvements in Hatbands, of which the following is a specification.

This invention relates to a novel construction of hat band, its object being to provide 10 a hat band for carrying fishing tackle, such as snell or gut hooks, flies, leaders, etc., and which will thus be of double service as an article of attire for fishermen and will at the same time enable parts of a fisherman's 15 equipment to be carried in a more convenient manner.

The invention consists of the features of construction, combination and arrangement of parts hereinafter fully described and 20 claimed, reference being had to the accompanying drawings, in which:—

Figure 1 is an outer side elevation of a hat band embodying my invention. Fig. 2 is an inner side elevation of the same. Fig. 25 3 is a cross-section on line 3—3 of Fig. 2.

Referring to the drawings, 1 designates the band made of leather or other suitable material, which is provided at one end with a buckle 2 and retaining loop 3 to receive the 30 other end of the band, which latter end is provided with a series of holes 4 to adjustably engage the tongue of the buckle.

Carried by the band are sets of hooked studs 5—5, 6—6 and 7—7, and between the 35 studs of each set the band is formed with sets of openings 5', 6' and 7', suitably arranged in spaced parallel pairs. The studs 5—5 and 7—7 are arranged in pairs at each end of the respective sets of openings 5' and 40 7'; while a single stud 6 is arranged at each end of the set of openings 6'. A lacing cord or thong 8, having its ends suitably united, as at 8', passes through the several sets of openings in such a manner as to provide 45 sets of crossed retaining strands 5^a, 6^a and 7^a between the respective sets of studs.

The studs 5 and strands 5^a are employed to hold a number of snell or gut hooks 9, the hooks of which are engaged with the studs, while the snells are passed beneath the 50 strands 5^a, whereby they are retained in position. The studs 6 and strands 6^a are employed to hold leaders 10, which are looped to engage said studs and have their free ends passed beneath said strands to retain them 55 in position. The studs 7 and strands 7^a are employed to hold flies 11, as will be readily understood.

It will thus be seen that an ornamental type of band is provided which embodies 60 means whereby hooks and associated elements of fishing tackle may be held thereon in a secure manner for convenience of the fisherman in carrying parts of his equipment. The band is at the same time unique 65 and attractive in appearance and may be either a permanent fixture or attachment to the hat, as desired.

I claim:—

As a new and improved article of manufacture, a hat band having means for connecting the meeting ends thereof, said band being provided between said meeting ends with a plurality of sets of spaced openings, each set comprising a series of openings arranged in pairs, a lacing thong of single length passed intermediately through the band near one end thereof and thence having its extremities threaded through the sets of openings and united near the opposite 80 end of the band, the threaded portions of the extremities providing sets of crossed retaining strands, and hooked studs carried by the band and arranged respectively at the opposite ends of each set of strands. 85

In testimony whereof I affix my signature in presence of two witnesses.

OTIS W. SCHOFIELD.
